DRAPERY FITTING

Julia B. Krajewski, Clifton, N. J.

Application March 25, 1948, Serial No. 17,009

1 Claim. (Cl. 248—215)

1

My invention relates to means for supporting flexible material, for instance, draperies and the like.

In present day building construction, windows are often disposed in immediate proximity to partitions or the like with the result that often, when a curtain rod is attached to the window frame for supporting curtains, at least one end of the rod, out of necessity, is so closely spaced to the partition as to make it impractical to attach the drape and valance supporting rods to the window frame in outward spaced relation with respect to the curtain rod. Furthermore, present day draping of windows contemplates the use of a single length of drapery material which is adapted to be secured, between its ends and at the upper corners of a window, in a manner to provide not only the depending side drapes but the valance extending between the drapes. Heretofore, so far as I am aware, devices for supporting draperies of this character have been attached directly to the window frames thus requiring appreciable space, which for the above reasons, is not always available. My invention overcomes the foregoing disadvantages and objectionable features and makes possible many advantages heretofore unobtainable.

One of the objects of my invention is to provide drapery holding means or fittings capable of being readily secured to the curtain rod in a manner to support the ends of the valance in a desired position with respect to the adjacent ends of the side drapes.

Another object of my invention is to provide means of the foregoing described character which is so constructed and arranged whereby a single length of material may be supported at the upper corners of a window in a manner to provide not only the side drapes but the valance.

A further object of my invention is to provide means of the foregoing described character which is simple in construction, durable in use, efficient in operation, and economical in manufacture.

An important object of my invention is to provide means of the foregoing described character capable of being attached to curtain rods already in use without employing tools and by persons other than those highly skilled in interior decorating and the like.

With the above and other objects in view, as will hereinafter appear, the invention consists in the combination and arrangement of parts hereinabove set forth and illustrated in the accompanying drawings from which the several features of the invention and the advantages at-

2

tained thereby will be readily understood by those skilled in the art.

Referring to the drawings wherein like reference characters designate like parts throughout the several views:

Figure 1 is a front elevation of the upper portion of a window frame equipped with a curtain rod having my invention applied thereto.

Figure 2 is a top plan view thereof.

Figure 3 is a side elevation of my novel form of drapery supporting member.

Figure 4 is a detail perspective view of the drapery supporting member and illustrating the same secured to the end of a curtain rod.

15 In practicing my invention, as illustrated in the drawing, I provide a window casing having the usual top and side sections 5 and 6, respectively, with the upper corners of the top section 5 having secured thereto brackets 7 which support the ends of a curtain rod 8 extending across the top section 5 and on which is supported window curtains 9. The curtain rod 8 is of a substantially rectangular configuration in cross section and may be of a sectional telescoping type.

20 As illustrated in the drawing, the sinistral side section 6 of the casing is disposed in close proximity to a building wall or partition 10 thereby limiting the space between the wall 10 and the adjacent bracket 7 to such an extent that it would be impractical to secure any means to the casing whereby the drapes and valance could be hung without presenting an untidy and crowded appearance. In order to provide suf-

30 ficient space for the drapes between the window frame and the wall 10, I provide a pair of drapery fittings or members 12 adapted to be secured to the curtain rod and over the curtain, adjacent the ends of the rod respectively, and in suffi-

35 cient spaced relation with any wall in close proximity to the frame so as to permit proper hanging and adjusting of the drapes and valance without crowding and presenting an untidy appearance.

40

45 Each of the members 12 is relatively long and narrow and is arched between its ends to provide a one-piece U-shaped body having end and bowed portions 13 and 14, respectively, with the bowed portion 14 connecting the end portions 13 together in spaced and parallel relation. The free end of one of the end portions 13 is reversely and outwardly bent to provide a curtain rod hook 15 for disposal over the rod 8. The section 16 of the hook, adjacent the jointure with the end portion 13, is outwardly and downwardly inclined 50 while the remaining section 17 is disposed in

substantial parallelism with the portion 13 to effect wedging of the curtain rod and curtain thereof within the hook for retaining the fitting in fixed position on the rod as illustrated in Figure 4.

When the fittings 12 are secured to the curtain rod 8 with the curtains 9 suspended therefrom, a length of drapery material is disposed within the bowed portions 14 of the members to provide the side drapes 18 and the valance 19 as clearly illustrated in Figure 1 of the drawing. Obviously, by adjusting the members 12 relative to the ends of the curtain rod 14, the distance required for disposing the drapes 18 between any adjacent wall and one of the members may be obtained to present a neat and tidy appearance. As will be apparent, my invention permits a one-piece length of drapery material to be used, without cutting, as the side drapes 18 and valance 19 to enhance the appearance of a window, it being understood that the valance 19 is arranged adjacent the members 12 to conceal the latter by having at least a fold thereof disposed over the front faces of the members. While in actual reduction to practice, I have constructed the members 12 of metal, it is to be understood that they may be constructed of any other desirable and suitable material. Furthermore, the material used may be somewhat resilient in order that the hooks 15 of the members may be securely clamped to the rod 8.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claim.

What I claim is:

In combination, a curtain rod adapted to be

supportingly attached to a window casing and having relatively narrow top and bottom faces and relatively wide and flat rear and front faces, a curtain mounted on said rod, and a drapery fitting secured to and supported by said rod and over said curtain, said fitting comprising a relatively long and narrow body of resilient material arched between its ends and defining a U-shaped member provided with spaced front and rear end portions, said rear end portion being disposed in parallelism with said front face and formed with an outwardly and reversely bent portion coacting with said rear end portion to define an inverted substantially U-shaped hook, said bent portion being provided with an end section disposed in parallelism with said rear face and with its lower end terminating in close proximity to said bottom face, said bent portion being formed with a coupling section extending over said top face and connecting said end section and said rear end portion together in spaced relation, said rear end portion coacting with said end section to clamp said member to said rod and over said curtain and thus enable said fitting to be supported by said rod and in turn support a valance trained through said member, said coupling section extending at an angle relative to said end section and said rear end portion to provide said hook with a cuneiform channel for receiving said rod to insure wedging and clamping engagement of said hook with said rod and over said curtain whereby to resist shifting of said fitting relative to said rod.

JULIA B. KRAJEWSKI.
